(57) **CLAIM**

The ornamental design for a cable retaining device for vehicle antenna, as shown and described.

DESCRIPTION

FIG. 1 is a perspective view of a cable retaining device for vehicle antenna showing our new design; FIG. 2 is a perspective view thereof; FIG. 3 is a perspective view thereof; FIG. 4 is a front elevation view thereof; FIG. 5 is a rear elevation view thereof; FIG. 6 is a right side elevation view thereof; FIG. 7 is a left side elevation view thereof; FIG. 8 is a top plan view thereof; FIG. 9 is a bottom plan view thereof; FIG. 10 shows the claimed design in the environment in which it is used; FIG. 11 shows the claimed design in the environment in which it is used; FIG. 12 shows the claimed design in the environment in which it is used; and, FIG. 13 shows the claimed design in the environment in which it is used.

The broken lines rendered in FIGS. 10-13 illustrates the environment of the claimed design and forms no part thereof.

1 Claim, 6 Drawing Sheets
